UNITED STATES PATENT OFFICE.

JACOB P. HOLTZHOUSER, OF NEW BRITAIN, CONNECTICUT, ASSIGNOR TO THE STANLEY WORKS, OF NEW BRITAIN, CONNECTICUT, A CORPORATION OF CONNECTICUT.

MOP.

1,174,574.

Specification of Letters Patent.

Patented Mar. 7, 1916.

Application filed September 22, 1914. Serial No. 863,009.

To all whom it may concern:

Be it known that I, JACOB P. HOLTZHOUSER, a citizen of the United States, and a resident of New Britain, in the county of 5 Hartford, State of Connecticut, have invented certain new and useful Improvements in Mops, of which the following is a specification.

The object of this invention is to provide 10 a new and useful connection between the handle and frame of a mop and resides in the certain features of construction herein-after described and more particularly pointed out in the claims.

15 The drawings illustrate one embodiment of the invention in which—

Figure 1 is a side view. Fig. 2 is a bottom view. Fig. 3 is a detail view.

Referring to the drawings, *a* denotes the 20 mop frame, which may conveniently be formed from a rod of metal bent to shape and having an offset *b*, at which point the connector is secured. The connector *c*, comprises a tubular body part *d*, at one end suitably threaded for engagement with the end 25 of the handle *e*. At its offset end, it is provided with two oppositely arranged hook-shaped members *f*, for engagement with the mop frame. As clearly seen in Figs. 1 and 30 2, after these hook members have been engaged with the mop frame the handle *e* can be screwed into the socket until its end bears against the mop frame between the hook members, constituting a frictional grip 35 which holds the handle in any desired position of adjustment with respect to the frame. Additional means for adjusting the handle with respect to the frame, are provided by the depending curved arms *g*, which have 40 a slight spring action and bear against the sides *h* of the offset portion *b*, having frictional engagement therewith. If desired, these arms *g* may be provided with a series of projections *i*, so spaced that the rod from 45 which the mop frame is made will lie between adjacent projections, which thus provide a somewhat positive grip on the frame, but which grip will be disengaged by turn-

ing the connector on the rod, which will force the arms *g* together as the rod rides 50 over the projections.

The structure is extremely simple, and 55 easy and economical to manufacture, and effective in providing an adjustable connector between the handle and the frame. 55

I claim as my invention:

1. A mop frame, a connector provided at one end with integral frame engaging means, and at its opposite end with a socket, and a handle secured in said socket and adjustable to clamp said frame between it and said 60 engaging means.

2. A wire mop frame, a connector provided at one end with integral hooked projections to rotatably engage said frame, and 65 at its other end with a socket, and a handle secured in said socket and adjustable to bind said frame against said hooked projections to fix said connector rotatably on said frame. 70

3. A mop frame offset in one portion to provide a lateral bar and side arms, a connector rotatably engaged with the lateral bar, yielding members thereon frictionally engaging the side arms, and a handle se- 75 cured to said connector.

4. The combination with a mop frame and handle, of a connector having hook members for engagement with said frame, yielding members on said connector adapted for frictional engagement with said frame, and means for securing said handle in said connector. 80

5. The combination with a mop frame and handle, of a connector provided with hook members for positive engagement with said frame, and yielding members adapted for frictional engagement therewith, projections on said yielding members adapted for co-operation with said frame, and means for 85 securing a handle in said connector. 90

JACOB P. HOLTZHOUSER.
